CLINTON EVANS WHITE, OF IRVINGTON, NEW JERSEY.

ADJUSTABLE MUSIC-ROLL SPOOL FOR AUTOMATIC MUSICAL INSTRUMENTS.

1,251,603.

Specification of Letters Patent.

Patented Jan. 1, 1918.

Application filed August 8, 1916. Serial No. 113,683.

To all whom it may concern:

Be it known that I, CLINTON EVANS WHITE, a citizen of the United States, and resident of Irvington, in the county of Essex and State of New Jersey, have invented certain new and useful Improvements in Adjustable Music-Roll Spools for Automatic Musical Instruments, of which the following is a specification.

10 My invention relates to spools for the music-rolls of self-playing musical instruments, and has for its object to provide an improved construction of such rolls, so as to secure an adjustment of the roll length, 15 within certain limits, and also to facilitate the proper re-rolling of the music-roll or sheet. To this end, my invention consists in a certain novel construction and arrangement of parts, as will be fully described in 20 the specification following hereinafter, and particularly pointed out in the appended claims.

Reference is to be had to the accompanying drawing, in which Figure 1 is a longitudinal section of my improved music-roll spool, showing the same adjusted to its maximum length; Fig. 2 is a partial longitudinal section, showing the right-hand portion of Fig. 1, adjusted to the position of minimum 25 spool length; and Fig. 3 is a cross section taken on the line 3—3 of Fig. 1.

The body A of the spool may be made of a tube of spirally-wound cardboard, or any other suitable cylindrical body adapted to 30 serve as a support for the music-sheet, generally of the well-known perforated character. At one end of this body I locate the stationary head B, having the customary diametrical slot B' for connection with the 35 mechanism which supports and winds or rotates the spool, said head being made, in the particular construction shown, with an axial inward projection B'' fitted into the adjacent end of the tubular body A, preferably with the interposition of a sleeve C (of cardboard or other suitable material) between said projection and the body A, said sleeve being fastened, as by gluing, both to the body A and to the head B. At the other 40 end of the body A is arranged the adjustable head D, formed with the customary cylindrical or slightly conical socket D' for the reception of the pin or like part of the mechanism which forms a support for that end of 45 the spool. Here too, a sleeve, E, is interposed between the axial inward projection

D'' of the head D and the adjacent inner surface of the body A, but whereas the sleeve C is generally longer than the projection B'', the sleeve E is shorter than the axial 60 projection or stud D'', being confined between the flange D* of the adjustable head D and an annular outward projection or bur D# at the inner end of said stud. The heads B, D are generally made of hard rubber, and the inner end of the stud D'' may be originally smooth, like the inner end of the stud B'', and the bur D# may be formed on said end, after the sleeve E has been placed on the stud D'', by pressing said 65 end against a heated metal plate. The sleeve E may be made of cardboard, and is of such a diameter as to engage the outer surface of the stud D'' with sufficient force to prevent accidental motion of the stud and head 70 relatively to the sleeve E, the latter being permanently or rigidly secured to the body A, as by gluing it thereto, but the inner surface of the sleeve has a loose (sliding) engagement with the cylindrical outer surface of 75 the stud D''. Thus, within the two limits represented in Figs. 1 and 2, the stud D'' and the entire head D may be adjusted in or out, lengthwise of the spool body A, thus altering the effective length of the said 80 spool; yet in each position, the frictional engagement of the inner surface of the sleeve E with the outer surface of the stud D'' will prevent any accidental lengthening or 85 shortening of the spool, that is to say, any 90 accidental sliding of the adjustable head relatively to the spool body.

The adjustability of the head D not only enables the spool to accommodate note-sheets or music-rolls of different widths (within 95 the limits of adjustment), but is also of great utility at the time of performing the re-rolling operation, or immediately prior thereto. Frequently, the sheet does not run quite straight, and in such cases the edge of the 100 sheet is liable to become injured by the flanges of the spool heads. If, however, at the beginning of the re-rolling operation, or immediately prior thereto, the adjustable head D of my improved spool is pushed inward by the operator until the flange D* presses against the edge of the sheet, the sheet will be brought into such a position that during re-rolling both edges will be in proper guiding engagement with the flanges 110 of the respective heads B and D, and that the sheet will travel perfectly straight dur-

ing re-winding and will therefore be coiled evenly on the spool.

Various modifications may be made without departing from the nature of my invention as set forth in the appended claims.

The frictional engagement between the adjustable head and the adjacent end of the body, or rather the sleeve which is rigidly secured within said tubular end, is sufficient to cause said head to turn with the body, whatever position the head may be adjusted to.

I claim as my invention:

1. A music-roll spool comprising a cylindrical body with heads at each end, one end of the body being tubular, and the head which is adjacent to said end being formed with a projection extending inwardly from the flange of the head into said tubular end portion of the body, the outer surface of said projection being cylindrical and out of contact with the inner surface of the body end, and the end of said projection being formed with a flange or stop projecting toward the inner surface of the tubular body end, and a sleeve secured to the said inner surface of the tubular body end and fitted between said stop and the flange of the head, in sliding en-

gagement with the cylindrical outer surface of said projection on the head, whereby said head may be adjusted relatively to the spool body lengthwise.

2. A music-roll spool comprising a cylindrical body with heads at each end, one end of the body being tubular, and the head which is adjacent to said end being formed with a projection extending inwardly from the flange of the head into said tubular end portion of the body, the outer surface of said projection being of uniform cross section and out of contact with the inner surface of the body end, and the end of said projection being formed with a flange or stop projecting toward the inner surface of the tubular body end, and a sleeve secured to the said inner surface of the tubular body end and fitted between said stop and the flange of the head, in sliding engagement with the outer surface of said projection on the head, whereby said head may be adjusted relatively to the spool body lengthwise.

In testimony whereof I have signed this specification.

CLINTON EVANS WHITE.
